Primary Examiner — Amy C Wierenga(74) *Attorney, Agent, or Firm* — Carter, DeLuca & Farrell LLP(57) **CLAIM**

The ornamental design for a griddle, as shown and described.

DESCRIPTION

FIG. 1 is a top perspective view of a griddle in accordance with the present design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view of the griddle thereof. The broken lines shown in the drawings illustrate portions of the griddle and its environment that form no part of the claimed design.
